BUTTON MAKING MACHINE

Emanuel Clemens, East Orange, N. J., assignor to
Peter C. Christensen, East Orange, N. J.

Application November 20, 1937, Serial No. 175,605

1 Claim. (Cl. 79—9)

My invention relates to button making machines and more particularly to button making machines of the type wherein discs or blanks of the material from which it is desired to make buttons are held in chucks while subjecting the same to turning operations, usually for the purpose of cutting the faces and/or the backs of the blanks to the forms desired in the finished buttons.

Button making machines of the type just referred to and which have gone into extensive commercial use are of several classes. In machines of one such class the chucks are generally rotatable about fixed or substantially fixed axes and certain operations necessary to be performed in using the machines, such as the insertion or placement of the blanks in the chucks, are executed manually. Machines of this class usually have a comparatively low output and require the continuous presence and services of attendants. In another class, a plurality of chucks are embodied in each machine, which chucks, while the machine is operated, are not only rotated about their several axes, but are moved bodily together or turret-wise in an annular path or orbit. At one point in such orbit the blanks to be worked on are delivered to the chucks as they successively reach such point, while at other points therein the blanks are successively gripped in the chucks, subjected to cutting operations and released by and removed from the chucks. Machines of the latter class, while usually automatic in their actions, are of complicated and costly construction, bulky, cumbersome in operation and frequently prove unreliable and unsatisfactory.

One of the principal objects of my invention is to provide an improved button making machine of the type employing a chuck or chucks for holding button blanks or discs to be operated on, which preferably is entirely automatic in its actions and requires so little and infrequent servicing that a single attendant can effectively take care of a considerable number of such machines.

Another object of my invention is to provide a machine of this character which is of improved and comparatively simplified construction and which is adapted to be effectively operated at such speed as to result in a very high output.

Another object of the invention is to provide a button making machine involving an improved construction and arrangement of parts whereby the various actions of the machine will be relatively timed to occur in the sequence necessary for

the proper and most effective operation of the machine.

Further objects of this invention are to provide such a machine having a plurality of chucks which are, preferably, although not necessarily, rotatable about fixed axes and which are alternately conditioned to grip and release button blanks to be operated upon when held therein; and also a machine of this character having novel means for delivering or applying such a blank to each of said chucks each time the latter is in release condition and preferably just prior to the changing thereof to gripping condition.

A further object is to provide in a machine having several chucks, means for delivering button blanks or the like to the chucks, which means comprises a simple and novel device for transferring such blanks or the like from a given point in the machine alternately to different chucks.

Another object of my invention is to provide novel means for ejecting button blanks or the like from the chucks of machines of the character described upon the changing of such chucks from gripping to release condition.

Another object of this invention is to provide an improved construction for ensuring the successive feeding of button blanks or the like in a machine of the character described, at definitely determined intervals.

Other objects, features and advantages of my invention will appear from the following description and the appended claim.

While my invention is especially designed for embodiment in button making machines having a plurality of chucks which are rotatable about fixed axes, it is to be understood that various features thereof, such, for example, as the blank feeding, delivering and ejecting means, are applicable to other types of button making machines and that some features are also adapted to be incorporated in machines used for purposes other than button making.

For a clearer understanding of the invention, attention is directed to the accompanying drawings which show a preferred form of button making machine in accordance with the invention and in which:

Figure 1 is a view of the machine in side elevation with parts broken away;

Figure 2 is a rear elevational view, partly broken away and partly in section, of the machine shown in Figure 1;

Figure 3 is a front elevational view, partly in section and partly broken away, of the head of

the machine shown in Figures 1 and 2 and certain of the parts associated with said head;

Figure 4 is an enlarged fragmentary longitudinal sectional view of the machine, with parts shown in elevation and with parts broken away;

Figure 5 is an enlarged sectional plan view of the machine, with parts broken away, the section being taken approximately on the line 5—5 of Figure 4;

Figure 6 is an enlarged fragmentary rear elevational and part sectional view of the machine, the line of the section corresponding approximately to the line 6—6 of Figure 5;

Figure 7 is an enlarged front elevational view, partly broken away and partly in section, of a portion of the machine corresponding to that shown in Figure 6;

Figure 8 is an enlarged sectional view, partly in elevation and partly broken away, taken on a line corresponding approximately to the line 8—8 of Figure 7;

Figure 9 is a detailed elevational view corresponding to the lower portion of Figure 7, with certain of the parts differently positioned;

Figure 10 is an enlarged detailed sectional view, partly in elevation, the section being taken approximately on line 10—10 of Figure 4;

Figure 11 is an enlarged detailed part sectional view showing the cutting tool in operative position;

Figures 12, 13 and 14 are detailed views illustrating the co-action and operation of certain parts shown in the upper portion of Figure 6;

Figure 15 is a sectional view taken on line 15—15 of Figure 8;

Figure 16 is a front elevation of one of the chucks with a button blank gripped therein as viewed from a plane indicated by line 16—16 in Figure 8; and

Figure 17 is a detailed sectional view showing a modified form of the button blank seating device which is associated with each chuck of the machine.

The frame of the machine shown in the drawings, comprises a main supporting head A, a base B to which said head is bolted, and a pair of spaced complementary vertical brackets or standards 1, 1' which are fixedly secured at their lower ends, as by bolts, to the enlarged upper end portion A' of the said head A. A member 2 in the form of a horizontal platform, is bolted at its ends respectively to the upper ends of brackets 1, 1' and acts to brace said brackets and to maintain their upper end portions in fixed spaced relation. A large cupped member C adapted to catch the cut buttons or the like discharged from the machine, is disposed between the head A and base B, said member having an upstanding central boss C' through which extend the bolts connecting the head A to base B and being thereby securely held in position.

The power for driving the various operating mechanisms and parts of the machine shown, is supplied by two electric motors M, M' which are respectively suitably supported by the brackets 1, 1' at the upper ends of the latter, as by having their frames bolted thereto.

The principal operating mechanisms of that particular form of my improved machine herein illustrated, comprise two chucking devices each of which includes a chuck for holding button blanks while being cut and means for ejecting cut blanks from the chuck, a pair of holding and feeding devices for two cutting tools which operate on button blanks held in the chucks re-

spectively, two grinding wheels for said cutting tools respectively, feeding mechanism for successively supplying blanks to a given point in the machine at regular intervals, and transfer mechanism for moving button blanks from said given point and delivering the same to said chucks.

The motor M' is relied upon to rotate only one of the chucks and one of the grinding wheels, whereas motor M in addition to rotating the other chuck and the other grinding wheel, also actuates the main driving shaft of the machine. Accordingly, motor M is preferably more powerful than motor M' and has a slower normal operating speed.

The shaft 3 of motor M has a pulley 4 fixed thereto; and by means of said pulley, a second pulley 5 fixed to a stud shaft 6, a belt 7 passing over both pulleys, a worm 8 carried by the stud shaft, and a worm wheel 9 engaged by the worm and keyed to the main shaft 10, the said motor is operatively connected to the main shaft so as to effect rotation thereof at the proper speed during operation of the machine. The stud shaft 6 is parallel to motor shaft 3 and is journaled in spaced bearings 11, 11 disposed within a journal-box 12 which is carried by a bracket 13 bolted or otherwise secured to the lower end portion of head A. The main shaft 10 is disposed at right angles to and slightly above stud shaft 6, being journaled in a bearing portion 14 of a rearward integral extension 15 of the head A. The shaft 10 projects from both ends of bearing portion 14; and keyed to one of the projecting end portions of said shaft are two cams 16 and 17, and to the other projecting end portion thereof are the worm wheel 9, two cams 16' and 17' respectively similar to cams 16 and 17, and a sprocket 18. Collars 19 mounted on shaft 10 and nuts 20 threaded onto its ends, act to maintain the members 16, 17, 9, 16', 17' and 18 properly spaced and to prevent appreciable axial movement of the shaft in the bearing portion 14.

The upper end portion A' of head A is provided with two similar cylindrical parallel openings 21, 21 extending therethrough from the front to the back thereof, in which openings the two chucking devices D, D' of the machine are respectively mounted. These chucking devices are identical in construction and each of the same, with special reference to Figures 8, 15 and 16, comprises a hollow generally cylindrical chuck 22 and a long hollow cylindrical clamping member or sleeve 23 having a stepped bore and within which said chuck is disposed. Each chuck 22 consists of an inner end portion 24 which fits fairly closely within the smallest section of the stepped bore of the respective clamping member 23, and three substantially equi-spaced resilient jaws 25 which are integral with said end portion 24 and extend forwardly therefrom through the larger sections of the bore of said clamping member to a point slightly beyond the forward end of the latter. The jaws 25 of each chuck terminate in gripping portions 26 which are biased away from each other to in-operative or non-gripping position or condition by the resiliency of said jaws. Adjacent their forward ends the jaws of each chuck are provided with conical or tapered outer surface portions 27, while the bore of the respective clamping member 23 is provided with an annular tapered forward end portion 28 which is adapted to co-act with the said surface portions 27 to force the chuck portions 26 to operative gripping position or condition against the action of the resilient jaws 25, as will pres-

ently appear. Each clamping member 23 is slidably mounted with a fairly close fit, in a pair of spaced cylindrical bearing members 29 and 30. Each bearing member 29 constitutes the inner raceway of an anti-friction bearing which also includes an outer ring raceway 31 and a series of balls 32 engaging annular grooves provided in the opposed surfaces of said raceways. The said ring 31 is seated in an enlarged forward end portion 33 of the respective opening 21 and is held firmly engaged with the shoulder 34 at the inner end of the said portion 33 by a flanged annular member 35 which is threaded into the latter and turned up tightly against the ring. The balls 32 and the grooves in the raceways 31 and 29 engaged thereby co-act to prevent longitudinal movement of the latter. Each bearing member 30 has a reduced end portion 36, and a ring 37 is held firmly engaged with the shoulder 38 at the inner end of such reduced portion by an annular member 39 which is threaded onto the latter and turned up tightly against the ring. This ring 37 constitutes the inner raceway of an anti-friction bearing which also includes an outer ring raceway 40 and a series of balls 41 engaging annular grooves formed in the opposed surfaces of said raceways. The ring 40 is disposed in an enlarged rear end portion 42 of the respective opening 21 and is held firmly engaged with the shoulder 43 at the inner end of the portion 42 by a flanged annular member 44 which is threaded into the latter and turned up tightly against said ring. The bearing member 30, clamping member 23 and chuck 22 of each chucking device, are connected to rotate together within the respective opening 21 by a stud 45 threaded into the member 30 and having a shank 46 which extends with a loose fit through a short slot 47 in member 23 and with a tight fit into an opening provided in the end portion 24 of the chuck. While the balls 41 co-act with the grooves in the raceways 37 and 40 engaged thereby to prevent movement of member 30 and therefore of chuck 22 longitudinally of the aforesaid opening 21, the slot 47 provides for such movement of the clamping member 23. A strong coiled compression spring 48 disposed about each clamping member 23 between a shoulder 49 on the latter and the corresponding member 30, biases such clamping member to a position in which its tapered inner end surface 28 co-acts with the tapered surfaces 27 of the jaws of the associated chuck and forces the portions 26 of said chuck to operative or gripping position.

The clamping member 23 of each chucking device extends a considerable distance rearwardly of head portion A', and a pulley 50 is secured to the rear end of said member as by having its hub threaded thereon and turned up tightly. A belt 51 passes over the pulley 50 of chucking device D and also over a pulley 52 fixed to the shaft 3 of motor M, and another belt 51' passes over the pulley 50 of chucking device D' and also over a pulley 52' fixed to the shaft 3' of motor M'. Therefore when the machine is in operation members 23 and 30 and chuck 22 of device D are rotatably driven by motor M, and the corresponding parts of device D' are rotatably driven by motor M'. The two pulleys 50 are preferably of equal diameter, and as the more powerful motor M has a slower operating speed than motor M', the pulley 52 is of greater diameter than pulley 52' so that both chucks will be rotated at substantially the same speeds.

Those portions of the clamping members 23 of

chucking devices D, D' located between the head portion A' and pulleys 50, are respectively embraced by yokes 53 and 53' formed at the upper ends of two vertically extending arms 54 and 54'. The said arms are respectively provided at their lower ends with apertured bearing portions or hubs 55 and 55' which are pivotally mounted on a rod 56 secured in spaced bosses 57 and 58 formed on head A, at points respectively outwardly of but closely adjacent said bosses. Respectively associated with the arms 54 and 54' are two vertically extending arms 59 and 59', the latter arms being provided with apertured bearing portions or hubs 60 and 60' which are respectively pivotally mounted on rod 56 between collars 61 fixed to the ends of the latter and the hubs of arms 54 and 54'. Lugs 62 and 63 provided on the hubs of arms 54 and 59 respectively and a screw 64 threaded through lug 62 and bearing against lug 63, constitute an adjustable connection between said arms whereby the relative angular position of the latter may be regulated. A similar adjustable connection between the arms 54' and 59' is constituted by lugs 62' and 63' on the hubs of said arms respectively and a screw 64' threaded through lug 62' and bearing against lug 63'. The arrangement of the parts just described is such that the yokes 53 and 53' are respectively in engagement with the hub ends of the adjacent pulleys 50 and the lower free ends of arms 59 and 59' are respectively in the paths of two lugs 65 and 65' which are respectively secured to and extend laterally from the cam 17 and the worm wheel 9. To minimize friction, the hub of each pulley 50 is provided with a recess 66 having an anti-friction bearing disposed therein, said bearing comprising inner and outer ring raceways 67 and 68 and a series of balls 69 engaging opposed annular grooves formed in the raceways. The raceway 68 is retained in recess 66 by a flat ring 70 which is suitably removably secured to the adjacent end of the pulley hub; and the inner raceway 67, which is free to rotate with respect to the pulley and the associated clamping member 23 and which is engaged by the adjacent yoke 53 or 53', is held against movement longitudinally of said pulley and clamping member by the co-action of the balls 69 with the grooves in the raceways engaged thereby. The lugs 65 and 65' are preferably angularly spaced 180 degrees with respect to the axis of main shaft 10. From the foregoing, it is apparent that when the machine is in operation, the yokes 53 and 53' will be quickly and alternately moved rearwardly once in each complete rotation of the main shaft by reason of the engagement of lugs 65 and 65' with the lower ends of arms 59 and 59' respectively. The yokes in such rearward movement thereof, force the pulleys 50 and clamping members 23 of the respective chucking devices D, D' rearwardly against the action of springs 48 to thereby effect the release of chucks 22 and the separation of the chuck jaws to non-gripping position. When the lugs 65, 65' pass from engagement with the respective arms 59, 59', springs 48 immediately act to move clamping members 23 forwardly thereby to effect the return of the respective chucks to gripping condition. Accordingly in each rotation of main shaft 10 the chucks 22 of the devices D, D' are momentarily and alternately placed, one time each, in releasing or non-gripping condition, but are firmly held or clamped in operative gripping condition during the major portion of each such rotation.

Associated with the chuck 22 of each chucking device are means adapted automatically to eject from the chuck a button or the like after the latter has been subjected to the facing cutting operation which the specific machine herein illustrated is designed to perform thereon, and immediately upon the placement of the chuck in releasing or non-gripping condition. There is preferably associated with said means a seat which is engaged by a button blank upon insertion thereof into the chuck as hereinafter described, thereby to ensure the proper positioning of the blank for the facing operation to be performed thereon while held by the chuck. Referring to Figures 8, 15 and 17, the said means, for each of the chucking devices, comprises a long tubular member 72 disposed within and extending axially of the chuck 22 and in which position it is supported from the chuck by a nipple 73 having internal and external screw-threaded portions respectively engaged with an externally threaded rear end portion of such tubular member and with an internally threaded rear end portion of the chuck section 24. The nipple 73 is turned into the chuck section 24 so as to bring a shoulder 74 provided thereon tightly against the rear end of said chuck section. A lock nut 75 threaded onto the rear end portion of member 72 and turned up tightly against nipple 73 serves to lock said member and nipple in the desired relative position. The rear end of member 72 is slotted at 76, so that upon loosening nut 75, said member may be turned by a screw-driver to effect longitudinal adjustment thereof with respect to nipple 73. The forward end portion of member 72 is reduced and has mounted thereon with a force fit a thimble or cap 77, the forward end wall of said cap preferably having a plane vertical face constituting a seat for button blanks inserted into the chuck. A long rod 78 extends loosely through the main portion of the bore of member 72 and with a fairly close fit through an opening in the end wall of thimble 77, and terminates at its rear end in a head 79 which is located in an enlarged rear end portion 80 of said bore. A compression spring 81 is disposed in the portion 80 between the head 79 and a plug 82 threaded into said portion. Spring 81, the effective action of which may be regulated by adjustment of plug 82, biases rod 78 to a position in which its head 79 engages the shoulder at the inner end of bore portion 80 and its forward end portion projects somewhat from the thimble 77. Therefore when a button blank S is inserted into the chuck to operative position against the thimble 77 it will engage and force rod 78 rearwardly and thereby compress and store energy in spring 81; and upon the subsequent release of the cut blank or button by expansion of the chuck jaws to non-gripping position, spring 81 will act under the energy stored therein, to return rod 78 quickly to its former position and thereby forcibly eject said blank or button from the chuck. The member 72 is so adjusted relatively to nipple 73 that when any button blank on which the machine is designed to operate, is seated against the front end of thimble 77 for gripping engagement at its edge by the chuck jaws 26, such blank will project somewhat forwardly from the chuck to enable the same to be faced properly by the associated cutting tool. When the blanks fed to the machine have curved backs, the thimble 77 is replaced by another thimble, as indicated at 77' in Figure 17, having a face conforming to the shape of said backs.

Facing tool holding and feeding devices E, E' are respectively co-operatively associated with the two chucks 22 of the chucking devices D, D'. The two assemblies which respectively include the devices E, E', facing tools T, T', grinding wheels G, G' and the means for mounting, controlling and actuating said devices and grinding wheels, are symmetrically disposed with respect to a vertical plane which extends substantially medially of the machine from the front to the rear thereof. These assemblies are also composed of similar parts which are similarly arranged. Therefore, I shall describe in detail but one of said assemblies, namely that which includes the device E. The parts of the other assembly, however, are designated by reference characters which, except for being primed, are the same as those designating the corresponding parts of the assembly which will now be described.

5 The device E comprises a holder 83 in which the facing tool T is frictionally secured, said holder being clamped for angular adjustment, as by a split collar portion 84 thereof and a co-operating bolt 85, to one end of a shaft 86 which

10 is journaled in and has both ends projecting from a bearing 87 provided at the upper end of a vertically extending member 88. This member 88 constitutes one arm of a rocker and is provided at its lower end with a hub 89 journaled on one end of a shaft 90 which is fixedly secured, as by a set screw 91, and has both ends projecting from an integral apertured projecting portion 92 of head A. The other arm 93 of said rocker is clamped for angular adjustment, by means of a split collar 94 integrally formed at one end thereof and a co-operating bolt 95, to the hub 89 of arm 88; the said arm 93 carrying at its other end a roller 96 bearing on the edge or camming surface of the cam 17 secured to main shaft 10.

15 A lug 97 on collar 94 of arm 93, spaced lugs 98 on the hub of arm 88 and screws 99 threaded through the lugs 98 constitute means whereby, upon loosening bolt 95, angular adjustment of arm 93 with respect to arm 88 may be effected; and a ring 100 secured by screws to the outer end of hub 89 and a screw 101 threaded into the corresponding end portion of shaft 90 and provided with a collar 102 having an annular groove engaged by said ring, constitute means whereby said hub and thereby both of arms 88 and 93, may be adjusted longitudinally of shaft 90 so as to obtain proper lateral positioning of tool holder 83 and the tool T therein and of arm 93 in relation to chucking device D and cam 17 respectively.

20 The grinding wheel G for sharpening tool T is secured to the inner end of a horizontal shaft 103 rotatably mounted in and projecting from both ends of a bearing 104 which is formed as an integral upper end portion of an arm 105. At its lower end arm 105 has spaced apertured portions 106 and 107 respectively loosely engaging the end portions of a rod 108 which extends through the arm 88 and is held in fixed position relative thereto by a set-screw 109. A lug 110 on portion 106, spaced lugs 111 on arms 88 and screws 112 threaded through the lugs 111 comprise means whereby arm 105 is held to the arm 88 for angular adjustment relative thereto so as to enable the driving belt for grinding wheel G to be suitably tensioned; and nuts 113 threaded on the ends of rod 108 outwardly of and adjacent the arm portions 106 and 107, are adapted to co-act with the latter to adjust arm 105 longitudinally of rod 108

25 and thereby adjust grinding wheel G to proper

lateral position with respect to tool T. The grinding wheel G is driven at high speed from motor M by pulleys 114 and 115, respectively secured to shaft 103 and motor shaft 3, and a driving belt 116 connecting and engaging over said pulleys. As the horizontal shafts 3 and 103 are at right angles to each other, the belt 116 is appropriately twisted between said pulleys. When the machine is in operation, only a slight angular movement of the rocker, comprising arms 83 and 93, about its pivotal axis takes place, and such movement does not result in any appreciable change in the distance between the axes of the motor shaft 3 and of the grinding wheel G.

The tool T consists of a thin flat strip of suitable metal, such as hard tempered steel, having a cutting end 117 shaped to turn button faces of desired form; and said tool is secured against the base 118 of holder 83 by means comprising a bar 119 overlying the tool and having pin and slot connections 120 with the holder, and an arm 121 pivoted to bar 119 and bearing at its end on the tool adjacent its cutting end. Bar 119 and arm 121 are adjustable lengthwise of the cutting tool T by a rod 122 having right and left handed screw-threaded connections with said bar and the holder 83 respectively. A lever 123 pivoted on holder 83 with one of its ends bearing against arm 121 and a screw 124 threaded through the other end of said lever and engaging the collar portion 84 of the holder, constitute means for holding said arm 121 pressed against tool T. It is apparent that the pressure with which arm 121 engages tool T and therefore the pressure with which the corresponding end portion of said tool engages its seat, may be regulated by adjusting screw 124. To stiffen the cutting end portion of tool T and to insure the same being rigidly held in proper operative position, a replaceable tool bearing and guiding member 125 is removably attached by screws 126 to the holder base 118; said member having in its upper face a groove or channel conforming to the width and thickness of the tool and an outer end 127 which conforms to the cutting edge of the tool and beyond which the latter, when operatively positioned in holder 83, projects only slightly (see Figure 11).

An arm 128 is clamped for angular adjustment, by a split collar portion 129 thereof and a co-operating bolt 130, to that end of shaft 86 remote from the one to which holder 83 is clamped; and secured to said arm 128 for adjustment in a slot 131 therein, is a pivot block 132. A link 133 is pivotally connected at one end to block 132 and at its other end to the arm 134 of a rocker which is pivoted on a rod 135 secured to the head A. The other arm 136 of said rocker carries a roller 137 which rides on the periphery or camming surface of cam 16. A strong tension spring 138 fixed at one end (not shown) and connected at its other end to the tiltable tool holder 83, acts through the latter, shaft 86, arm 128, link 133 and the rocker comprising arms 134, 136, to maintain roller 137 firmly engaged with cam 16; and said spring also acts through said holder and the rocker comprising arms 83, 93, to hold roller 96 engaged with the cam 17. The camming surface of cam 16 consists of a high circular portion concentric with shaft 10 and a low portion 139 which is of much less angular extent than said high portion. Accordingly during the greater part of each rotation of main shaft 10, when the roller 137 engages the high portion of cam 16, the holder 83 is maintained horizontal in operative relation to the chuck of device D; and

during the remaining part of each rotation of said shaft, as roller 137 rides on the low portion 139 of said cam, the said holder is first tilted downwardly about the axis of shaft 86 to bring tool T into engagement with grinding wheel G, the tool is sharpened by reason of such engagement and the holder is then returned to horizontal position.

The edge of cam 17 comprises a major portion 10 concentric with main shaft 10 and a slightly higher eccentric portion 140 which as the roller 96 rides thereover, (referring now to Figure 4) effects a slight counterclockwise pivotal movement of the rocker comprising arms 83 and 93. 15 The eccentric portion 140 is in such angular relation to the low and high camming surface portions of cam 16 that this counterclockwise movement of said rocker is effected, in each rotation of main shaft 10, directly after tool holder 83 is 20 returned from its tilted tool-sharpening position to its horizontal position (shown in Figure 4), whereby there will then be imparted to the tool holder a movement toward chucking device D sufficient to effect the facing, by the tool T, of a button held in the chuck of said device. Obviously as the roller 96 passes from the eccentric cam portion 140, the said rocker will be swung in a clockwise direction to thereby effect movement of the tool holder 83 away from the chucking device D and the retraction of tool T from cutting position. The cams 16 and 17 respectively differ from cams 16' and 17' only in that the low and high camming surface portions 139 and 140 of the former are respectively angularly spaced approximately 180° from the corresponding camming surface portions of the latter. By reason of this angular spacing the tool holders 83 and 83' will, in the operation of the machine, be alternately horizontally positioned in operative relation to the respective chucking devices D and D', be alternately moved, when so positioned, toward the respective chucking devices to effect the cutting or facing of buttons held in the chucks thereof, and be alternately tilted to and from tool-sharpening position.

Means are provided whereby the tool T will be advanced a very slight amount in its holder 83 when, after each cutting or facing operation performed by the tool, said holder is tilted from horizontal position towards tool-sharpening position, the construction and arrangement being such that said tool will be thus advanced before its holder reaches the latter position. This advancing means comprises a lug 141 which engages the inner end of tool T and is integral with an internally threaded block 142 mounted on a threaded shaft 143. The shaft 143 is disposed in a cylindrical recess 144 provided in the base 118 and has its end portions journaled in said base. 50 Lug 141 projects upwardly through a slot 145 in base 118, rotary movement of block 142 being thereby prevented. Shaft 143 projects from that end of holder 83 which is remote from chucking D, and secured to its projecting end portion is 55 a worm wheel 146 which meshes with a worm 147 carried by a short shaft 148 journaled in lugs 149 on the holder. Secured to the shaft 148 is a ratchet 150 with which a pawl 151 co-operates to impart rotary movement to said shaft. The pawl 151 is carried by an arm 152 which is pivotally mounted at its lower end on shaft 148, said pawl being maintained in engagement with ratchet 150 by a spring 153 which has its ends respectively connected to the pawl and the arm 152. A link 154 is pivotally connected at one

end to the upper end portion of arm 152 and at the other end to the upper end of an arm 155 which is fixed to and projects upwardly from the bearing 87 of rocker arm 83 in which shaft 86 is journaled. As arm 155 is vertical and fixed with respect to rocker arm 83, it is apparent that a change in the relative angularity of holder 83 and rocker arm 83 will through link 154, cause swinging movement of arm 152 in one direction or the other, on shaft 148. For example, when holder 83 is moved in a clockwise direction (see Figure 4) from its tilted tool-sharpening position to horizontal position, link 154 causes arm 152 to swing on shaft 148 in a counter clockwise direction. During such movement of arm 152 the pawl 151 merely ratchets over the teeth of ratchet wheel 150. When holder 83 is moved in a counter clockwise direction, however, as in the tilting of the same downwardly from horizontal position to engage tool T with wheel G, link 154 causes arm 152 to swing in a clockwise direction, whereupon the pawl 151 co-acts with a tooth of wheel 150 to impart rotary movement to the latter and therefore to the shaft 148, which, in turn, through worm 147 and worm wheel 146, results in a slight rotary movement being imparted to the threaded shaft 143. Such movement of shaft 143 causes block 142 to be fed lengthwise of the same and the lug 141 of said block to advance the tool T slightly in holder 83 to a position where it will be sharpened properly upon subsequent engagement thereof with the abrasive wheel G.

Bolted to the upper end portion A' of head A between the brackets I, I', is a bracket 156 having a long vertical upwardly extending arm or portion 157. Suitably secured in fixed position to the upper end of bracket arm 157 is an inclined hopper 158 for the buttons or the like to be faced or operated on by the machine. Means is provided for feeding buttons successively and at substantially predetermined intervals from the hopper 158 to a vertical chute K and for delivering the buttons to said chute with the desired sides thereof facing outwardly. This means is of well-known construction and will not be described in great detail: briefly, it comprises a circular plate 159 rotatably mounted within hopper 158 adjacent the bottom of the latter and having a plurality of long slots (not shown) which extend substantially radially thereof and are angularly equi-spaced; a shaft 160 which is secured at its upper end to said plate and which is adapted to be driven at constant speed, as will later be described; and an opening (not shown) in the bottom of the hopper, said opening being so located and formed that in each rotation of plate 159, the inner end portions of the slots in the latter will be successively registered therewith and a button will be discharged therethrough from each of said slots into the upper flared end K' of chute K with the proper side of such button facing outwardly.

The shaft 160 extends loosely through the bottom of hopper 158 and is journaled in and has its lower end projecting from an apertured lug or extension 161 of bracket arm 157. Keyed to the lower end of shaft 160 and held thereon by a nut 162 are a bevel gear 163 and a cam 164. Meshing with gear 163 is a smaller bevel gear 165 which is secured to one end of a horizontal counter-shaft 166 journaled in spaced bearings 167 provided on the rear side of bracket arm 157. The counter shaft 166 is parallel to main shaft 10 and is adapted to be driven from and at the same speed as the latter by a chain

168 which engages over the sprocket 18 and over another sprocket 169 which is secured to the counter shaft and is of the same size as sprocket 18. Keyed to the shaft 166 are three cams 170, 171 and 172, the functions of which will presently be explained. Collars 173 set-screwed to shaft 166, bearings 167 and gear 165 serve to maintain these cams properly spaced.

The rotatable plate 159 disposed in hopper 158 10 of the specific machine herein disclosed, is preferably provided with eight of the radially extending slots mentioned above. Accordingly in each rotation of the shaft 160, eight buttons are discharged one after the other from the hopper 15 into the chute K which directs them to a seat M whence, by means hereinafter described, buttons are transferred and delivered alternately to the chucks of devices D, D' for the facing thereof by tools T, T'. However, during each rotation 20 of main shaft 10 only two buttons are faced, viz. one by tool T while held in the chuck of device D and one by tool T' while held in the chuck of device D'; and as counter shaft 166 rotates at the same speed as said main shaft, the shaft 160 25 should be rotated at a speed which is only one-fourth that of the said shafts 10 and 166 whereby during a complete rotation of each of the latter shafts, but two buttons will be discharged into chute K and conducted to seat M. Therefore the bevel gear 165 has only one-fourth as many teeth as bevel gear 163 so that shaft 160 will be driven from shaft 166 at a four to one speed reduction.

The chute K comprises a long vertical channel 174 terminating at its upper end adjacent the opening in the bottom of hopper 158 and at its lower end a slight distance above the seat M; said channel being formed by the front face of bracket arm 157 and two spaced vertical guide members 175 and 176 which are respectively secured, as by screw and slot connections 177 and 178, to said bracket arm for lateral adjustment in order that the width of the channel may be so regulated as properly to accommodate buttons 40 of the particular size or diameter which are to be faced by the machine at any time. The channel 174 is substantially closed at the front thereof by similar opposed plates 179 and 180 respectively secured to guide member 175 and 176 45 so as to partially overlie said channel, and by two doors 181 and 182 which are respectively mounted for movement about vertical and horizontal axes adjacent the lower and upper ends of said channel and are spring-biased to closed 50 position against said guide members. The said doors provide for ready access to channel 174 55 in case the button blanks become stuck or clogged therein.

The seat M is formed by the walls of a V-shaped notch 183 provided in the upper portion of a plate 184 which is secured to bracket arm 157 for vertical adjustment by a screw and slot connection 185. The point of V-notch 183 is aligned with the vertical central axis of channel 174, and therefore the center of each button blank, upon the latter coming to rest on seat M after being fed thereto from hopper 158 through channel 174 will be so aligned. As above indicated, the machine is adapted for operation on blanks of different sizes; and in adapting the machine to any change in the size or diameter of the blanks to be faced, the plate 184 is always adjusted to such a position that every blank passing through the machine will 60 upon being seated in notch 183, be accurately

centered with respect to a single definite fixed point.

The dimensions of chute 174 are such that the button blanks are very loose therein but are held substantially vertical while passing therethrough. Therefore in their descent through said chute, the blanks wobble and engage the walls of the chute with varying degrees of friction, and the time of such descent varies considerably for different blanks. Each button blank, however, is disposed in seat M only momentarily and is then picked up and carried to one or the other of the chucks 22 of devices D, D'; and it is highly important that the blanks successively delivered to seat M be so delivered at exactly equal time intervals and in definitely timed relation to other operations of the machine. For this purpose, I have provided suitable means preferably comprising a stop in the form of a lever 186 which is pivoted at 187 on an extension of bracket arm 157 for horizontal swinging movement and which is biased by a spring 188 to operative position with its free end located adjacent and directly below the lower end of chute 174. The movements of lever 186 to and from operative position are controlled or effected by the cam 164 and a bell crank lever pivotally mounted at 189 on bracket arm 157 for movement about a horizontal axis. The said bell crank lever has a lower arm 190 loosely connected to lever 186 by a pin 191, and an upper arm 192 carrying a roller 193 engaging the camming surface of cam 164. The spring 188, through the lever 186 and said bell crank lever, acts to maintain roller 193 firmly but yieldingly thus engaged with cam 164. The annular camming surface of cam 164 consists of eight similar equi-spaced low portions 194 and a like number of similar equi-spaced high portions 195 disposed intermediately of said low portions. Accordingly eight times in each rotation of shaft 169 and therefore two times in each rotation of counter-shaft 166, at definite and equal intervals, the stop 186 is moved to and from operative position. In the normal operation of the machine, each time stop 186 is brought to operative position it arrests and momentarily supports one of the button blanks being successively fed through chute 174 to the seat M, and upon the subsequent movement of said stop to inoperative position such blank is released and drops in a substantially vertical position to said seat.

While each button blank is engaged with seat M, it is maintained in vertical position adjacent the front of bracket arm 157 by a vane or gate 196 which is secured to a pivot pin or screw 197 and which is supported by the latter on said arm for vertical swinging movement adjacent the face of plate 184. The pivot pin 197 extends through bracket arm 157 and has secured to its rear end an arm 198. A vertically extending link 199 is pivotally connected at its lower end to arm 198 and at its upper end to another arm 200, which latter arm is pivoted at 201 to an extension of one of the bearings 157 for vertical movement. Arm 200 underlies the cam 170 and has a high portion which is constantly maintained in engagement with said cam by a tension spring 202 secured at its ends respectively to the pivot pin connecting said arm and link 199 and to a pin 203 secured in bracket arm 157. The cam 170 thus controls and effects the movement of gate 196 to and from its operative position in front of the seat M, the construction and arrangement being

such that said gate is moved downwardly to open or inoperative position and also upwardly to closed or operative position two times in each rotation of counter shaft 166; said downward movements being respectively effected directly after the two button blanks successively fed through chute 174 during such rotation of said counter shaft reach seat M and just before said blanks are picked up from said seat and are respectively transferred to the chucks of devices D, D', and said upward movements being effected respectively directly after said blanks are so picked up and transferred.

An important feature of my invention is the means for picking up each of the button blanks which are successively fed to the seat M and transferring the same from said seat alternately to the chucks of devices D, D'. This means, which may be of various forms, is preferably pneumatic, or at least partially pneumatic, in action. That form of said means in the machine herein illustrated, comprises a long tubular member 204 mounted for rotary and sliding movements in a cylindrical opening 205 which extends through the enlarged portion A' of head A in parallel relation to the openings 21, 21 and is disposed above and midway between the axes of the latter openings. The tubular member 204 extends forwardly from head A, and disposed with a tight fit in the forward end portion of said member and projecting therefrom is a tube 206 having its projecting portion bent into a substantially semi-circular form and constituting a goose-neck 207. Applied to the end of goose-neck 207 with a force fit is a hollow cylindrical nipple 208. The tube 206 with the goose-neck 207 is secured to tubular member 204 so as to partake of all longitudinal and rotary movements of the latter, as by a bar 209 which has at one end an apertured enlargement 210 engaged with a force fit over a reduced portion of nipple 208 and which has at the other end a split apertured portion 211 clamped securely to the forward reduced end portion of said member 204 by a cooperating screw bolt 212. The split portion 211 is held against the shoulder formed by the reduced end portion of member 204 by a nut 213 threaded onto said end portion and turned up tightly. A flexible tube 214 is connected at one end to the rear end of member 204 and at the other end to a suitable exhaust fan (not shown) which is constantly operated when the machine is in use, and which may be driven by either of the motors M, M' or by a separate motor. Therefore during operation of the machine, air is continuously withdrawn from member 204 and tube 206 and is replaced by air sucked in through the nipple 208. This nipple accordingly acts as a suction nozzle or cup adapted to pick up and hold a button or the like thereagainst when brought in contact therewith or closely adjacent thereto.

When the machine is in normal operation there are automatically imparted to the tubular member 204 such rotary and longitudinal movements as to cause the suction nozzle or cup 208 successively to pick up the two buttons which are fed one after the other to seat M in each rotation of main shaft 10, and to transfer one of said buttons to the chuck of device D and the other to the chuck of device D'. The construction whereby these movements are imparted to member 204 in the proper sequence and timed relation will now be described.

Tubular member 204 is provided on the portion thereof within the opening 205 with a segmental gear 215, said gear having an angular extent of somewhat more than 180 degrees and preferably comprising teeth which are formed, by milling on in any other suitable manner, as integral parts of said member. The gear 215 is engaged by another segmental gear 216 (an arcuate slot 217 formed in the portion A' of head A providing for such engagement) constituting the end portion of the vertical arm of a bell crank lever 218 which is pivotally mounted at 219 on a standard 220 provided on bracket 156. A vertical rod or link 221 has its lower end pivotally connected at 222 to the end of the horizontal arm of said bell crank lever and its upper end pivotally connected at 223 to a lever 224 which is pivoted at 225 to the bracket arm 157. Lever 224 carries a roller 226 which rides on the camming edge surface of cam 171. A strong tension spring 227 connected at one end to a rod 228 carried by standard 1 and at the other end to a pin 229 carried by bell crank lever 218, biases the latter to a position wherein the vertical arm thereof will engage an adjustable stop screw 230 which is threaded through a lug on bracket 156 and the teeth at the extreme right of gear 216 (referring to Figure 6) will be in engagement with the gear 215. The angular position of lever 218 and therefore of tubular member 204, under the action of spring 227, is controlled by cam 171 through lever 224 and link 221. Cam 171 comprises diametrically opposite high and low portions 231 and 232 and two similar diametrically opposite portions 233 and 234 of intermediate height as compared to the said portions 231 and 232 and disposed between the latter. Each of said cam portions 231, 232, 233 and 234 has a central section which is concentric with the axis of the cam 171 and constitutes a dwell. The construction is such that with roller 226 resting on the dwell of cam portion 233 bell crank lever 218 will be in the angular position shown in Figure 6, with the central teeth of gear 216 engaging the central teeth of gear 215 on tubular member 204, and the latter will occupy an angular position in which the goose-neck 207 is substantially vertical with its suction cup 208 opposite the seat M, as shown in Figure 9; and in the next complete rotation of shaft 166 in the direction of the arrow shown in Figure 14, during which roller 226 rides from the cam portion 233, over the cam portions 232, 234, and 231, in that order, and then returns to the said portion 233, the goose-neck 207 as viewed from the front of the machine is successively swung about the axis of member 204 in a clock-wise direction to a position in which suction cup 208 is opposite the chuck 22 of device D, in an anti-clockwise direction to vertical position with said suction cup again opposite seat M, further in an anti-clockwise direction to a position in which said cup is opposite chuck 22 of device D', and finally in a clock-wise direction back to vertical position with said cup still again opposite seat M. The face of plate 185 having the seat M and the front ends of both chucks 22 lie in a common vertical plane, and during the swinging movements imparted to goose-neck 207 as described, the suction cup 208 is maintained in its foremost position wherein it is spaced a slight distance forwardly of said plane. Whenever tubular member 204 and the goose-neck 207 are swung to any angular position in which the cup 208 is opposite the seat

M or either of the two chucks 22, the same are maintained in such angular position for a brief period because of the fact that the roller 226 on lever 224 then rides on one of the aforesaid dwell sections of the cam portions 233, 232, 234 and 231. During each of the brief periods member 204 and goose-neck 207 are maintained in any of the said angular positions, the member 204 is rapidly reciprocated or moved longitudinally rearwardly and then forwardly in the opening 205 by mechanism which will be hereinafter described. These reciprocatory movements imparted to member 204 are slight, being merely sufficient to ensure the cup 208 being brought into contact with or closely adjacent a button lodged in the seat M so as to pick up the button by suction when said cup is positioned opposite said seat, and to ensure the insertion of a button carried by the cup within the gripping portion of each chuck 22 when said cup is positioned opposite the latter. The teeth of gear 215 are made of such length as to permit such reciprocatory movements of member 204 without disruption of the engagement of said gear and the gear 216.

Secured, as by screws, to plate 185 is a bar 235 having a vertical notch 236 with which the bar 209 engages and coacts accurately to centralize or align the cup 208 in respect of the seat M when said cup is moved toward the latter during reciprocations of member 204. As shown in Figures 7 and 9, the bar 235 is provided rearwardly of the notch 236 with a cut-out or recess 237 which accommodates the gate 196 when the latter swings downwardly to open position.

Threaded into and extending rearwardly from head A is a rod 238 to which a vertical triangular plate 239 is suitably secured for angular adjustment. Threaded through plate 239 are two screws 240 having smooth reduced forward end portions 241 which are respectively accurately aligned with the axes of the two chucks 22. Lock nuts 242 serve to secure the screws in properly adjusted position. Adjustably clamped to the rear end portion of tubular member 204, somewhat forwardly of plate 239, is a bar 243 having at its free end an opening 244 with which the reduced end 241 of each of the screws 240 is adapted to engage with a fairly close fit. Accordingly when the suction cup 208 is opposite either of the chucks 22 and then moved toward the chuck during rearward movement of member 204, the opening 244 of bar 243 will be engaged over the end 241 of the corresponding screw 240 and coact therewith accurately to align or centralize the cup with respect to said chuck.

The rear portion of tubular member 204 is reduced, and secured thereto, as by being threaded thereon and turned up tightly against the shoulder at its forward end, is a sleeve 245 having spaced collars 246. A bell crank lever 247 comprising lower and upper arms 248 and 249 and a pivot rod 250 to the ends of which said arms are respectively secured, is pivotally mounted by means of said pivot rod on a bracket 251 bolted to the head portion A'. The lower end portion of arm 248 is in the form of a yoke 252 and embraces sleeve 245 between the collars 246. A link or rod 253 has one of its ends pivotally connected at 254 to the upper end of arm 249 and its other end pivotally connected at 255 to the upper end of a lever 256 which has its lower end pivoted at 257 on the bracket arm 157. Adjacent its upper end lever 256 carries a roller 258

which rides on the camming edge surface of cam 172 and is held firmly engaged therewith by a strong tension spring 259 secured at one end to bracket arm 157 and at the other end to the link 253 adjacent the pivot 254. Cam 172 comprises four equi-spaced convex sections 260 whose edge surfaces are equal circular segments of the same radius, and four like equi-spaced concave sections 261 which are shorter than sections 260 and alternate with the latter. With the construction just described, the tubular member 204, in each complete rotation of shaft 166, is maintained against longitudinal movement and with the suction cup 208 in its aforesaid foremost position, as roller 258 rides over each of the convex sections 260 of cam 172, while as said roller rides over each of the four comparatively short concave cam sections 261, member 204 is rapidly reciprocated or longitudinally moved rearwardly and forwardly a short distance. The construction and relative arrangement are such that, as herein before indicated, member 204 and cup 208 are thus held in their foremost positions during each of the rotary movements imparted thereto by cam 171 and its associated parts, while such member and cup are held against rotary or angular movement during each of the said reciprocatory movements imparted thereto, when cup 208 is opposite one or the other of the chucks 22 or the seat M, because the roller 226 will then be riding on one of the dwell sections of the portions 231, 232, 233 and 234 of cam 171.

For removing the shavings and chips cut from the buttons in facing the same, there may be provided, as shown by broken lines in Figure 2, a pipe or conduit 262 having branches 263 and 264 which respectively terminate adjacent the chucks 22 of devices D, D'. The conduit 262 is connected to a suitable exhaust fan having the base thereof, indicated at 265 in Figure 2, bolted to the brace member 2. This exhaust fan may be driven by either of the motors M, M', or if desired, by a separate motor.

To render the parts disposed within the openings 21 of head portion A' accessible for servicing or other purposes, said head portion is provided with two elongated substantially rectangular slots or openings 266 which respectively communicate with openings 21 and which are normally closed by readily removable covers 267.

While believed to be apparent from the foregoing, the operation of the machine will now be briefly described. In each complete rotation of main shaft 10 and of counter shaft 166, two buttons or button blanks are successively fed from hopper 158 to chute K; and by reason of the provision of stop lever 166 and its actuating and controlling means including cam 164, the buttons thus fed to chute K are successively delivered from the latter to seat M at time intervals which, for any given speed of operation of the machine, are practically exactly equal. As each button or the like is thus delivered to seat M the gate 196 is in closed or operative position; but directly after the button comes to rest on the seat, said gate is moved downwardly to open or inoperative position by its controlling and actuating mechanism which includes cam 170. The suction cup 208, which now occupies a position opposite seat M, thereupon has successively imparted thereto, by the actuating and controlling mechanisms which respectively include the cams 172 and 174, a reciprocatory or rearward and forward movement wherein it picks up the button and removes it from said seat; a swinging movement about

the axis of member 204 of such extent and in such a direction as to bring the same opposite to that one of the chucks 22 which is then in expanded or non-gripping condition and from 5 which a faced button has just been ejected by the associated spring biased rod 78; another reciprocatory movement wherein the button carried thereby is partially inserted within the gripping portions 26 of the jaws 25 of said chuck 10 and said jaws are contracted, as herein before described, to grip the button and detach or remove it from the cup; and then another swinging movement of the same extent as but in the opposite direction of its preceding swinging movement so as again to bring the cup opposite seat M. The gate 196 will then have been returned to its operative or closed position and the next button fed to chute K after that transferred by cup 208 to one of the chucks 22 as just described, 15 will then be disposed in seat M. In the following button-transferring actuation of tubular member 204 and suction cup 208, the latter will effect the removal of the said next button from seat M and the insertion thereof within the 20 jaws of the other chuck 22. As will be understood, during the movements which are necessary to be imparted to tubular member 204 and cup 208 to effect the transfer of a button from seat M to the chuck of either one of the devices 25 D, D', the cutting tool T or T' associated with such device is retracted from cutting position, swung downwardly with its holder 83 or 83' to bring it into operative relation with the associated grinding wheel G or G', and is advanced 30 slightly in its holder when so swung to ensure effective sharpening thereof by said grinding wheel; and as the tool and its holder are swung downwardly the chuck of said device is adjusted to non-gripping position and the button which has just been faced while held therein is ejected by the associated rod 78. Also, in the meantime, the facing tool and tool-holder associated with the other chucking device are swung upwardly from tool sharpening position to a horizontal operating position and then moved toward said chucking device to effect the facing of the button then held in the chuck of such device. It is thus apparent that the machine is entirely 35 automatic in its actions, and that when it is in use practically the only manual operation required to maintain the same in operation at maximum efficiency is the replenishing of the supply of button blanks in hopper 158 from time to time.

40 The disks or blanks designed to be faced by the machine shown and described herein may be formed of any suitable material capable of being effectively turned such, for example, as cured or partially cured casein material, vegetable ivory, synthetic resin materials, etc.

45 While the machine shown and specifically described herein is a preferred form and admirably adapted to fulfill the stated objects, it is to be understood that such form is merely illustrative and is subject to many changes and various modifications without departure from the spirit of the invention or the scope of the appended claim.

50 What I claim is:

55 Feed mechanism for button-shaped work pieces comprising an open sided seat to which such work pieces are adapted to be fed; a gate mounted for movement to and from an operative position in front of and adjacent the open side of said seat to close said open side and to maintain a work piece in a certain position on the seat;

60

65

70

75

means for so moving said gate; a device for gripping a work piece through said open side and transferring a work piece from said seat to a remote point, said device being mounted for movement to and from a gripping position relative to the open side of said seat; means for so moving said device; means for actuating the mov-

ing means for said gate and device; and means for so controlling the operation of said actuating means that movement of the gate from its said operative position will be effected upon each 5 movement of said device to its gripping position through the open side of said seat.

EMANUEL CLEMENS,
